TROUSERS OR SIMILAR ARTICLE

William B. Murphy, Crandall, Tex.

Application January 18, 1951, Serial No. 13,852

Term of patent 14 years

(Cl. D3—17)

To all whom it may concern:

Be it known that I, William B. Murphy, a citizen of the United States, residing at Crandall, in the county of Kaufman and State of Texas, have invented a new, original, and ornamental Design for Trousers or Similar Article, of which the following is a specification, reference being had to the accompanying drawing, forming part thereof:

Figure 1 is a front perspective view of the trousers or similar article, embodying my new design.

Figure 2 is a rear perspective view, and

Figure 3 is a side elevational view thereof.

The characteristic feature of my design resides in the combination on the trousers disclosed of a plurality of superimposed vertically shaped chevron-like strips on the front and rear of each trouser leg, the front and rear strips being interposed at their ends on the outer seams of the trousers by substantially diamond shaped

figures, the latter figures being superposed by a larger diamond shaped figure which in turn is superposed by a plurality of short, vertical bars in horizontally spaced relationship. The chevron-like strips are interposed at their ends on the inner leg seams by vertical strips, one on each side of the seams. The cuff on each trouser leg is ornamented by a plurality of circumferentially spaced vertical bars, all as shown.

I claim:

The ornamental design for trousers or similar article, substantially as shown and described.

WILLIAM B. MURPHY.
